Primary Examiner — Rosemary K Tarcza(74) *Attorney, Agent, or Firm* — D'Ambrosio & Menon, PLLC; Usha Menon(57) **CLAIM**

The ornamental design for a charge interrupting device, as shown and described.

DESCRIPTION

FIG. 1 is a corner perspective view of a charge interrupting device showing our new design;

FIG. 2 is a rear elevational view of a charge interrupting device; and,

FIG. 3 is a top plan view of a charge interrupting device.

1 Claim, 3 Drawing Sheets(56)
